GAS REGULATOR PEDAL ATTACHMENT

Edmond Ojalvo, New York, N. Y.

Application February 27, 1943, Serial No. 477,392

10 Claims. (Cl. 74—526)

This invention relates to speed control devices for automobiles, particularly of the type adapted for attachment to gas pedals for limiting the operative movement thereof.

On certain occasions operators of motor cars find it necessary to make provision for preventing the car from attaining more than a predetermined speed. In times of national emergency this may be due to maximum speed limits set by law for gas and tire conservation purposes. In normal times speed limitations may also be deemed advisable during initial driving periods of a new car; or they may be necessary for personal reasons. The methods employed for effecting such speed limits can generally be said to fall into two classes, those wherein the maximum opening of the throttle valve is controlled by a governor device, and those wherein the gas pedal is prevented from being depressed more than a predetermined amount by some stop device.

The former of these methods is generally intricate in nature, costly to install, and not readily subject to variation or adjustment except by an expert. Devices of the latter class are generally simpler in construction than those of the governor type; but the known commercial embodiments of such devices are frequently difficult to set, not easily adjustable, and not conveniently capable of being released from their obstructing or operating positions.

It is within the contemplation of my invention to provide a device of the latter class adapted for ready attachment to a gas pedal, and not having any of the aforesaid shortcomings. And in this aspect of my invention, it is an important object to enable a gas regulator of the last mentioned class to be readily set for providing a predetermined maximum limit to the speed of the car.

It is another object of this invention to enable an operator to adjust the device for maximum speeds of the car within the limits determinable by the entire range of the pedal, without the use of any special skill and without the necessity of the operator leaving his seat.

It is still another object of this invention to enable the device to be quickly released into its inoperative position so that if desired or necessary, as in the case of an emergency, the speed of the car can be quickly increased as the circumstances would justify.

And it is within the further contemplation of my invention to provide a device capable of accomplishing the aforesaid objects, yet which is simple in construction and easy to install.

Other objects, features, and advantages will

appear from the drawing and the description hereinafter given.

Referring to the drawing,

Figure 1 is a side part-sectional elevation of my invention shown operatively associated with the floor board of an automobile, the parts being shown by broken lines in their operative position.

Figure 2 is a front view of the device looking from line 2—2 of Figure 1.

Figure 3 is a section of Figure 1 taken along line 3—3.

Figure 4 is a section of Figure 1 taken along line 4—4, and

Figure 5 is a fragmentary section like that in Figure 1, of the pawl and rack mechanism shown in the retracted or releasing position.

The form of my invention illustrated in the drawing contains a supporting member 10 comprising a base 11 attached to the forward part of a conventional gas or "accelerator" pedal 12 by fasteners 13, and, preferably integral with the base, a casing 14 containing therein a chamber 15 through which extends a plunger 16. Said plunger is longitudinally movable through said casing, the upper portion thereof extending through the opening 17 in the casing, and the lower portion thereof extending through the lower opening 18 therein.

The bottom terminal of the plunger 16 is preferably expanded and in the form of a rounded or semi-spherical base or foot 19 adapted for abutment with the floor board 20 of the car in a manner to be hereinafter set forth. The upper portion of said plunger is provided with a rack

21 whose teeth 22 are adapted to be operatively engaged by the slideable pawl 23. The pawl is slidably supported by the bracket 24 which is mounted by threaded means over and is supported by the member 10, said bracket also in-

cluding the arm 25 and bearing 26 rotatably supporting the shaft 27 for purposes to be herein-after set forth. The pawl 23 is yieldably urged by spring 28 into engagement with the teeth of the rack 21, and is retractably actuated to the inoperative or releasing position shown in Figure 5, by release mechanism to be now described.

Pivotedly mounted upon gas pedal 12 is the release pedal 29 normally urged upwardly by spring 30, the forward end of the release pedal containing the bifurcated extension 31 (Figure 4) with which the lower terminal of link 32 is in pivotal engagement. Said lower terminal is provided with pins 33 in slideable and rotatable engagement with slots 34 in said extension 31, in conventional manner, to permit a proper pivotal connection.

The said link 32 contains the arm 35 extending through the slot 36 in the pawl, the upper portion of the arm being provided with the cam 37 engageable with the surface 38 of the walls of slot 36. Thus, upon a downward movement of the release pedal 29, the resultant downward movement of the cam 37 will cause a retraction of the pawl 23 to its inoperative position shown in Figure 5.

Contained within the chamber 15 of the casing 14, and surmounted over the plunger 16, is the helical spring 39, the lower portion thereof being in abutment with the floor or base of chamber 15, and the upper portion being in abutment with the collar 40 affixed to plunger 16. When the plunger is in its upper or inoperative position, the said spring 39 is preferably in an unstrained condition. In said inoperative position of the plunger, it is preferred that the lowermost part 41 of the plunger shoe 19 be at a level slightly above that of the bottom surface 42 of the gas pedal 12.

The upper portion of the plunger 16, preferably above the rack 21, is pivotally connected to the arm 43 which is fixedly attached to shaft 27. In the embodiment illustrated, the upper terminal 44 of arm 43 is bifurcated, containing slots 45 in slidable and rotatable engagement with pins 46 attached to the upper terminal of plunger 16, to permit the desired pivotal movement. Fixedly attached to shaft 27 is also the arm 47, the free end of which is connected to a link or string 48 adapted for manual grasping, so that a pull in the direction of the arrow (Figure 1) will cause a clockwise rotation of arms 47 and 43 and a downward movement of the plunger 16.

In the operation of this device the operator, knowing the maximum limiting speed at which he desires to set the device, depresses the gas pedal while operating the car until such speed is attained. For the purpose of our illustration, the position of the gas pedal for such speed is represented by the broken lines of Figure 1. At this point the operator pulls the arm 47 towards himself by applying the pull directly to the arm or to the link 48. Such a pull will cause a downward projection of the plunger, as aforesaid, until the plunger foot 19 strikes the floor 20 as indicated by the broken lines in Figure 1. This downward movement is resisted only by the yieldable action of the spring 39, the pawl slidably engaging the teeth 22 of the rack 21 during such downward movement of the plunger. After the lowermost position is reached, the pawl 23 will prevent an upward return of the plunger, inasmuch as the pawl is in operative engagement with the upwardly directed teeth of the rack under the influence of the spring 28.

It is thus apparent that by the simple expedient of manually actuating the arm 47, the required maximum car speed is set according to the lowermost possible position of the gas pedal. In similar manner the pedal can be adjusted for any other position. The fineness of the adjustment is dependent upon the number and size of the teeth 22 of the rack, the finer the teeth the more minute the adjustment.

Should it be desired to release the device from its speed-limiting position, all that need be done is to depress the release pedal 29, which will forthwith cause a retraction of the pawl from its holding position thereby permitting the spring 39 to return the plunger to its inoperative position.

It will be noted that the upward movement of

the plunger is limited to its normal retracted position by the engagement of the shoe 19 with the base 11. It is also to be observed, as aforesaid, that the level of the lowermost point 41 of the plunger shoe 19 is above the bottom surface 42 of the gas pedal when the device is in its inoperative position, the base being elevated to accommodate said shoe. This arrangement permits the pedal to be depressed downwardly to its lowermost operative position without interference by the shoe when it is desired to run the car in normal manner.

It is understood that the embodiment above described and shown in the drawings is illustrative of my invention and not employed by way of limitation, inasmuch as numerous changes and modifications may be made therein, within the scope of the appended claims, without departing from the spirit of this invention.

What I claim is:

1. In combination with the gas pedal of an automobile, a device for limiting the operative movement of the pedal comprising a supporting member attached to the pedal and immovable with respect thereto, a plunger slidably supported by said member, the plunger being movable between a predetermined normal retracted position at which the lower terminal of the plunger is at a level not below the undersurface of the pedal, and a predetermined maximum projected position at which said lower terminal is below said undersurface, the said lower terminal of the plunger being abuttable with the floor of the car, yieldable means normally maintaining said plunger in its retracted position, manually manipulable means for depressing said plunger to a selected projected position below said retracted position, whereby the maximum downward movement of the pedal will be correspondingly limited, and holding means for operatively maintaining said plunger in any projected position against the action of said yieldable means.

2. In combination with the gas pedal of an automobile, a device for limiting the operative movement of the pedal comprising a supporting member attached to the pedal and immovable with respect thereto, a plunger slidably supported by said member, the plunger being movable between a predetermined normal retracted position at which the lower terminal of the plunger is at a level not below the undersurface of the pedal, and a predetermined maximum projected position at which said lower terminal is below said undersurface, the said lower terminal of the plunger being abuttable with the floor of the car, yieldable means normally maintaining said plunger in its retracted position, manually manipulable means for depressing said plunger to a selected projected position below said retracted position, whereby the maximum downward movement of the pedal will be correspondingly limited, holding means for operatively maintaining said plunger in any projected position against the action of said yieldable means, and releasing means associated with said holding means for releasing it from its operative holding position, whereby the plunger will be returned to its retracted position under the influence of said yieldable means.

3. In a gas regulator pedal attachment adapted for operative use with the gas pedal of an automobile, a supporting member adapted for attachment to the gas pedal, a plunger slidably supported by said member and adapted for movement relative to the pedal between a nor-

mal retracted position and a maximum projected position a predetermined distance therebelow, the lower terminal of the plunger being abuttable with the floor of the car, yieldable means normally maintaining said plunger in its retracted position, means for depressing said plunger to a selected projected position below said retracted position, whereby the pedal will be held against downward movement when the plunger is in engagement with the floor, and holding means for operatively maintaining said plunger in any projected position against the action of said yieldable means.

4. In a gas regulator pedal attachment adapted for operative use with the gas pedal of an automobile, a supporting member adapted for attachment to the gas pedal, a plunger slidably supported by said member and adapted for movement relative to the pedal between a normal retracted position and a maximum projected position a predetermined distance therebelow, the lower terminal of the plunger being abuttable with the floor of the car, yieldable means normally maintaining said plunger in its retracted position, means for depressing said plunger to a selected projected position below said retracted position, whereby the pedal will be held against downward movement when the plunger is in engagement with the floor, holding means for operatively maintaining said plunger in any projected position against the action of said yieldable means, and foot-operated releasing means adapted for attachment to said pedal and associated with said holding means for releasing it from its operative holding position, whereby the plunger will be returned to its retracted position under the influence of said yieldable means.

5. In a gas regulator pedal attachment adapted for operative use with the gas pedal of an automobile, a hollow casing adapted for attachment to the gas pedal, a plunger extending through and slidably supported by said casing, said plunger being adapted for movement relative to the pedal between a normal retracted position and a maximum projected position a predetermined distance therebelow, the lower terminal of the plunger being abuttable with the floor of the car, yieldable means normally maintaining said plunger in its retracted position, a pivotally mounted manually manipulable arm in operative engagement with the upper portion of the plunger for imparting downward operative movements thereto, whereby the plunger may be depressed to a predetermined projected position for holding the gas pedal against downward movement when the lower terminal of the plunger is in engagement with the floor, and holding means engageable with said plunger for holding it against retraction when in a projected position.

6. In a gas regulator pedal attachment adapted for operative use with the gas pedal of an automobile, a supporting member adapted for attachment to the gas pedal, a plunger slidably supported by said member and adapted for movement relative to the pedal between a normal retracted position and a maximum projected position a predetermined distance therebelow, the lower terminal of the plunger being abuttable with the floor of the car, yieldable means normally maintaining said plunger in its retracted position, manually manipulable means for imparting downward operative movements to the plunger, whereby the plunger may be depressed to a predetermined projected position for hold-

ing the gas pedal against downward movement when the lower terminal of the plunger is in engagement with the floor, retractile holding means engageable with said plunger for holding it against retraction when in a projected position, and pedal means adapted for hinged attachment to said gas pedal and operatively connected with said holding means, whereby upon an operative actuation of the pedal means the holding means will be retracted to operatively release said plunger.

7. In a gas regulator pedal attachment adapted for operative use with the gas pedal of an automobile, a casing adapted for attachment to the gas pedal, a chamber within said casing, a plunger extending through said chamber and casing and slidably supported by the walls of said casing, said plunger being adapted for movement relative to the pedal between a normal retracted position and a maximum projected position a predetermined distance therebelow, the lower terminal of the plunger being abuttable with the floor of the car, spring means within said chamber normally urging the plunger into its retracted position, a pivotally mounted manually manipulable arm in operative engagement with the upper portion of the plunger for imparting downward operative movements thereto, whereby the plunger may be depressed to a predetermined projected position for holding the gas pedal against downward movement when the lower terminal of the plunger is in engagement with the floor, toothed means on said plunger, a slideable pawl yieldably urged into operative engagement with said toothed means for holding the plunger against retraction when in a projected position, and means to retract said pawl from its holding position, whereby the plunger will be returned to its retracted position under the influence of said yieldable means.

8. In a gas regulator pedal attachment adapted for operative use with the gas pedal of an automobile, a base member adapted for attachment to the gas pedal, a casing mounted upon said base, the underside of the base being adapted for positioning at a level a predetermined distance above the underside of the pedal, a plunger extending through and slidably supported by said casing, said plunger being adapted for movement relative to the pedal between a normal retracted position and a maximum projected position a predetermined distance therebelow, the lower terminal of the plunger containing an expanded portion abuttable with the floor of the car when the plunger is in a projected position and abuttable with the underside of said base when the plunger is in its retracted position, yieldable means normally maintaining said plunger in its retracted position, means for depressing said plunger to a selected projected position below said retracted position, whereby the pedal will be held against downward movement when the plunger is in engagement with the floor, and holding means for operatively maintaining said plunger in any projected position against the action of said yieldable means.

9. In a gas regulator pedal attachment adapted for operative use with the gas pedal of an automobile, a base member adapted for attachment to the gas pedal, a casing mounted upon said base, the underside of the base being adapted for positioning at a level a predetermined distance above the underside of the pedal, a plunger extending through and slidably supported by said

casing, said plunger being adapted for movement relative to the pedal between a normal retracted position and a maximum projected position a predetermined distance therebelow, the lower terminal of the plunger containing an expanded portion abuttable with the floor of the car when the plunger is in a projected position and abuttable with the underside of said base when the plunger is in its retracted position, yieldable means normally maintaining said plunger in its retracted position, a pivotally mounted manually manipulable arm in operative engagement with the upper portion of the plunger for imparting downward operative movements thereto, whereby the plunger may be depressed to a predetermined projected position for holding the gas pedal against downward movement when the said expanded portion of the plunger is in engagement with the floor, retractile holding means engageable with said plunger for holding it against retraction when in a projected position, and foot-operated releasing means adapted for attachment to said pedal and operatively connected to said holding means, whereby upon an operative actuation of the releasing means the holding means will be retracted to operatively release said plunger.

10. In a gas regulator pedal attachment adapted for operative use with the gas pedal of an

automobile, a supporting member adapted for attachment to the gas pedal, a plunger slidably supported by said member and adapted for movement relative to the pedal between a normal retracted position and a maximum projected position a predetermined distance therebelow, the lower terminal of the plunger being abuttable with the floor of the car, yieldable means normally maintaining said plunger in its retracted position, manually manipulable means for imparting downward operative movements to the plunger, whereby the plunger may be depressed to a predetermined projected position for holding the gas pedal against downward movement when the lower terminal of the plunger is in engagement with the floor, toothed means on said plunger, a pawl yieldably urged into operative engagement with said toothed means for holding the plunger against retraction when in a projected position, retracting means engageable with said pawl, and pedal means adapted for hinged attachment to said gas pedal and operatively connected with said retracting means for retracting the pawl from its holding position, whereby the plunger will be returned to its retracted position under the influence of said yieldable means.

EDMOND OJALVO.
